(57) **CLAIM**

The ornamental design for a luggage case, as shown and described.

DESCRIPTION

FIG. 1 is a top front right perspective view of a design for a luggage case, in a zipped and snapped configuration.

FIG. 2 is a top front left perspective view of the design for the luggage case, in a zipped and snapped configuration.

FIG. 3 is a top front right perspective view of the design for the luggage case, in an unzipped, snapped, and shelves-stowed configuration.

FIG. 4 is a top front left perspective view of the design for the luggage case, in an unzipped, snapped, and shelves-stowed configuration.

FIG. 5 is a top front right perspective view of the design for a luggage case, in an unzipped, unsnapped, and shelves-deployed configuration.

FIG. 6 is a top front left perspective view of the design for a luggage case, in an unzipped, unsnapped, and shelves-deployed configuration.

FIG. 7 is a front view of the design for a luggage case, in an unzipped, unsnapped, and shelves-deployed configuration.

FIG. 8 is a rear view of the design for a luggage case, in an unsnapped configuration.

FIG. 9 is a left view of the design for a luggage case, in an unzipped, unsnapped, and shelves-deployed configuration.

FIG. 10 is a right view of the design for a luggage case, in an unzipped, unsnapped, and shelves-deployed configuration.

FIG. 11 is top view of the design for a luggage case, in an unzipped, unsnapped, and shelves-deployed configuration; and,

FIG. 12 is a bottom view of the design for a luggage case, in an unsnapped configuration.

The portions shown in the drawings in dashed lines do not constitute part of the claimed design.

1 Claim, 12 Drawing Sheets
